(57) CLAIM

The ornamental design for a suspended boxing bag, as shown and described.

DESCRIPTION

FIG. 1 is a perspective view of a suspended boxing bag showing our new design.

FIG. 2 is a front elevation view of FIG. 1.

FIG. 3 is a side elevation view of FIG. 1.

FIG. 4 is a top view of FIG. 1; and,

FIG. 5 is a bottom view of FIG. 1.

The means for suspending the suspended boxing bag is shown in broken lines for illustrative purposes only and forms no part of the claimed design.
